SASH CONSTRUCTION

William S. Hamm and Harry D. Seyison, Elkhart, Ind., assignors to The Adlake Company, Chicago, Ill., a corporation of Illinois

Application November 15, 1933, Serial No. 698,032

(Cl. 189—76)

2 Claims.

This invention has to do with sash construction, and is particularly concerned with the way in which the rail members are jointed together at the corners.

The corner joint arrangements which have been used in the past in connection with sheet metal rail members do not give satisfactory results when used with rail members made of thin sheet aluminum, due to the inherent characteristics of that metal and the difficulties experienced in obtaining a strong and tightly closed joint at the miter.

The principal object of the invention is to provide an improved form of connection between the rail members, which connection is especially effective at the lower corners of the sash where the greatest strains occur, and is particularly applicable to sheet aluminum rail members although not in any way limited in its application to the same.

Another important object is to provide an improved way of securing the L-shaped corner inserts to the sheet aluminum without liability of the edges of the screw apertures in the aluminum being forced out of shape by the strains to which the rail members are ordinarily subjected.

While the foregoing statements are indicative in a general way of the nature of the invention, other objects and advantages will be apparent to those skilled in the art upon a full understanding of the improved corner joint construction.

A preferred embodiment of the invention is presented herein for the purpose of exemplification, but it will of course be appreciated that the invention is susceptible of embodiment in other structurally modified forms coming equally within the scope of the appended claims.

In the accompanying drawings:

Fig. 1 is an inside face view of the right hand side of a thin-walled sheet aluminum sash, in which the rail members have been joined together at the corners in accordance with the present invention;

Fig. 2 is a sectional view through the lower right hand corner of the sash, taken on the median plane of the sash, with the glass and glazing strips removed and with the end portions of the rubber side rail extension and rubber bottom rail sealing strip broken away for clearness;

Fig. 3 is a perspective view of the lower corner insert shown in Fig. 2, with a portion of one of the side flanges broken away;

Fig. 4 is a perspective view of the lower corner strap shown in Fig. 2;

Fig. 5 is a sectional view through the upper

corner of the sash, taken on the median plane of the sash, with the glass and glazing strips removed and with the upper portion of the rubber side rail extension broken away;

Fig. 6 is a perspective view of the insert shown in Fig. 5;

Fig. 7 is a vertical section through the top rail, taken on the line 7—7 of Fig. 5;

Fig. 8 is a horizontal section through the side rail, taken on the line 8—8 of Fig. 5;

Fig. 9 is a horizontal section through the side rail, taken on the line 9—9 of Fig. 2;

Fig. 10 is a horizontal section through the side rail, taken on the line 10—10 of Fig. 2; and

Fig. 11 is a vertical section through the bottom rail, taken on the line 11—11 of Fig. 2.

In order to save space and avoid repetition, only the right-hand side of a sash is shown in Fig. 1, but it will of course be understood that the left-hand side is merely a duplication of the right-hand side. The joint in the lower right-hand corner of the sash is had between a horizontally extending bottom rail 10 and a vertically extending side rail 11. In the particular sash structure shown, the bottom rail 10 is provided with a lock 12 of the type disclosed in Larson Patent No. 1,857,294, and the side rail 11 is provided with a rubber extension strip 13 of the character set forth in an earlier application filed by William S. Hamm bearing Serial No. 610,645, but these features have no bearing on the present invention other than to the extent to which they may affect the cross-sectional shaping of the rail members and the reinforcement 14 in the lower corner of the sash.

The rail members 10 and 11 are made of thin sheet aluminum and the abutting ends of such members are mitered at 15. The ends are telescoped over the legs 16 and 17 of the previously mentioned reinforcement 14, which reinforcement consists of an L-shaped aluminum filler block. The horizontally extending leg 16 of the block, which extends into the end of the bottom rail 10, is provided with upwardly extending side flanges 18 (see Fig. 3) and is also provided with a deep channel 19 between the flanges in which the bolt 20 of the lock 12 is adapted to slide. The flanges 18 project upwardly into the narrow side grooves 21 (see Fig. 11) which are formed in the upper portion of the bottom rail by the presence of the reentrant glazing groove 22. The vertically extending leg 17 of the block is provided with somewhat similar flanges 23 which project into the narrow grooves 24 (see Fig. 9) in the side rail 11. An aperture 25 is cut in the lower por-

tion of the leg 17, in alignment with the bottom and sides of the channel 19, to accommodate the nose of the bolt 20. As will be observed, the cross-sectional shapes of the legs 16 and 17 of 5 the block are such as to provide a snug fit of the legs within the ends of the rail members.

At the time that the ends of the rail members are telescoped over the ends of the block 14 into abutment with each other at the miter 15, 10 an L-shaped metal strap 26 (see Fig. 4) is applied to the outer edges of the rail members at the corner in spanning relation to both members. In the particular embodiment shown the horizontally extending leg 27 of the strap is positioned flatly 15 against the outer edge 28 of the bottom rail in the groove 29 provided for the rubber sealing strip 30 while the vertically extending leg 31 of the strap is positioned flatly against the outer edge 32 of the side rail in the 20 groove 33 provided for the base portion 34 of the rubber extension strip 13. After the parts have been assembled in the manner described, the strap, rail members and filler block are drawn tightly together by screws 35 and 36 and the 25 rail members and filler blocks are further drawn together, beyond the ends of the strap, by additional screws 37 and 38. The tapped holes in the block which receive the screws 35 and 36 are conically counterbored at 39 and 50 (see Figs. 30 10 and 11), and the thin sheet aluminum portion of the edges of the rail members at the locations of the screw apertures are conically countersunk at 41 and 42. The screws employed have conical 35 heads 43, which heads are drawn tightly into the countersunk portions of the rail members in the counterbored portions of the block, resulting in a firm clamping fit which precludes of any tearing or deformation of the thin aluminum material at the location of the fastening means. 40 The same type of counterbored and countersunk interlock between the rail members and block is also provided at the location of the end screws 37 and 38.

By using the strap 26 in conjunction with the 45 filler block 14 a very strong and rigid corner joint is produced with a close and permanent fit of the mitered edges 15. In the particular embodiment shown the strap 26 is provided, below the screw 35, with a rectangular aperture 44 for the reception of the bolt 20, but in those sash structures wherein a higher bottom rail is employed, the screw 35 can be positioned below the bolt, permitting the strap to terminate flush with the lower edge of the bolt and obviating the 50

necessity of an aperture for the accommodation of the latter.

The upper corner of the sash, between the side rail member 11 and the top rail member 45, contains another L-shaped block 46 (see Fig. 6), 5 which block has a vertically extending leg 47 which projects down into the upper end of the side rail member 11 and a horizontally extending leg 48 which projects into the end of the top rail member. The leg 48 of the block is 10 fastened in the adjacent end of the top rail member 45 by screws 49, which screws preferably clamp countersunk portions 50 of the upper edge of the rail member down into counterbored seats 51 in the block. The leg 47 of the block is fastened 15 in a little different way however in the upper end of the side rail member 11, owing to the fact that the leg 47, along with the top rail member 45, must be withdrawn vertically from the side rail member 11 before the sash can be glazed or 20 reglazed. For this reason, the apertures 52 in the outer edge of the member 11 are beveled without being countersunk, thereby permitting removal of the leg 47 of the block as soon as the 25 screws 53 have been taken out.

We claim:

1. In sash construction, two hollow thin-walled sheet metal rail members arranged in right angular abutment with each other at one of the lower corners of the sash, an L-shaped filler block positioned within the ends of the rail members at the corner, an L-shaped strap positioned against the outer edges of the rail members at the corner, and fastening means for the block and strap extending through both the block and the strap and the interposed portions of the rail members.

2. In sash construction, two hollow thin-walled aluminum sheet metal rail members provided with glazing grooves at their inner edges, said members being arranged in right angular mitered abutment with each other at one of the lower corners of the sash, an L-shaped aluminum filler block positioned within the ends of the rail members at the corner and provided with spaced flanges which embrace the side walls of the glazing grooves, an L-shaped sheet metal strap positioned against the outer edges of the rail members at the corner, and means passing through the block and the strap and one end of one of the rail members in the median plane of the sash for releasably fastening the parts together.

WILLIAM S. HAMM.
HARRY D. SEVISON.
